INVENTOR

Cleveland F. Dunderdale

United States Patent Office.

CLEAVELAND F. DUNDERDALE, OF NEW YORK, N. Y.

Letters Patent No. 100,737, dated March 15, 1870.

IMPROVED APPARATUS FOR FORCING AIR INTO CARBURETERS ON RAILROAD CARS.

The Schedule referred to in these Letters Patent and making part of the same.

I, CLEAVELAND F. DUNDERDALE, of New York city, in the county and State of New York, have invented certain Improvements in Apparatus for Forcing Air to be Carbureted for Illuminating and Heating Purposes, of which the following is a specification.

The nature of my invention relates to the employment of a double trumpet-pipe blower with swinging valve, and a pipe connected with a receiver, to contain a supply of air under pressure, which is placed on top of a railroad car or locomotive, and arranged in such a manner that the moving of the car or locomotive causes a pressure of air down the pipe leading from the blower into the receiver, where it is kept under pressure, and distributed through pipes leading therefrom to a suitable carbureting device for carbureting the same with the vapors of a hydrocarbon liquid placed therein for producing an illuminating gas, or for heating purposes.

Figure 1 is a side elevation of a machine embodying my invention.

A are the funnel-shaped blowers, placed parallel with the moving car or locomotive, having a wide trumpet mouth on each, which meet into one pipe at B. The motion of the car causes a current of air to pass down the funnel into pipe B.

C is a swinging valve, placed between the two blowers, so that a current of air passing in one blower causes the valve to swing against the other blower opening, preventing its passing directly through and deflecting it downward into pipe B.

D is a trap, arranged to collect dust and cinders that may be blown down.

E is a wire-gauze, placed in pipe F to sift the air of its particles of dust.

G, is a receiver, made like a bellows, to rise and fall according to the quantity of air contained therein.

H is a cord or chain, attached at its upper end to the inside top of the bellows receiver, having its lower end fastened to a valve shown at I, which, when the bellows-top rises to its full extent, the tightening-cord lifts the valve I, and permits the excess of air to pass out, thereby preventing a great strain on the sides of the bellows receiver.

J is a pipe leading from the receiver to the vessel

containing the hydrocarbon liquid, where it is to be carbureted, and from thence passes to the burners, where it is to be consumed.

A single rotary funnel blower may be used instead of a double one, which would be stationary. In using a single blower, a large fan-tail rudder would be necessary to keep the mouth of the blower to the wind.

The operation is, that when a train or car starts, the motion thereof causes a current of air to pass in the funnel A, causing valve C to swing to the opposite side. The air is thence deflected into pipe B; passing down the same, enters pipe F, passing through the sieve E, which precipitates the dust into trap D.

Passing through pipe F the air enters the bellows G, inflating the same, which, on rising to its full extent, opens by means of cord H the valve I, when the air then passes out through said valve until the air is drawn out from the bellows receiver through pipe J, when the valve closes, and the receiver is again filled as fast as drawn off. The receiver is made of sufficient size to contain enough air to supply the burners for several hours, should the motion of the car cease for that length of time.

I claim as my invention—

1. Using the motion of railroad-trains, while moving, for forcing the atmospheric air, by atmospheric resistance, into a receiver for holding the air, and giving a steady pressure thereto for the purpose of carbureting the same for illuminating, heating, &c., substantially as and for the purpose hereinbefore set forth.

2. The blower A or its equivalent, the valve C or its equivalent, pipe B, trap D, sieve E or its equivalent, pipe F, receiver G with cord and valve H and I or their equivalents, and outlet-pipe J, when arranged substantially as and for the purpose hereinbefore set forth.

3. The above, in combination with any air-carbureting device for carbureting atmospheric air for illuminating, heating, and other purposes.

CLEAVELAND F. DUNDERDALE.
